United States Patent Office.

JOSEPH H. ATWATER, OF PROVIDENCE, RHODE ISLAND.

Design No. 4,390, dated October 11, 1870.

DESIGN FOR A BLACK-BOARD ERASER.

The Schedule referred to in these Letters Patent and making part of the same.

To all whom it may concern:

Be it known that I, JOSEPH H. ATWATER, of Providence, Providence county, in the State of Rhode Island, have invented and produced a new and original Design for Black-board Erasers; and I hereby declare the following to be a full and exact description thereof, reference being had to the accompanying drawing forming part of this specification.

The nature or essence of my invention consists in the design for a black-board eraser represented in the above-mentioned drawing, the same consisting of a wedge-shaped block, provided with a handle, as shown.

I cover one, two, or more of the flat sides of the wedge-shaped block with sheep or lamb-skin, having the wool on, or with other suitable stuff for rubbing chalk-marks from a black-board; but

What I claim as my invention is—

The design or configuration for a black-board eraser, as described and shown.

JOSEPH H. ATWATER.
